(57) **CLAIM**

The ornamental design for a controller for electronic device as shown and described.

DESCRIPTION

FIG. 1 is a perspective view of front, top and left side of a controller for electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 of FIG. 6;

FIG. 9 is a cross-sectional view taken along line 9-9 of FIG. 6;

FIG. 10 is a perspective view showing a transforming state thereof;

FIG. 11 is a perspective view showing a first usage state thereof;

FIG. 12 is a perspective view showing a second usage state thereof; and,

FIG. 13 is a perspective view showing a third usage state thereof.

The broken lines on the controller for electronic device depict portions of the controller that form no part of the claimed design. The broken lines showing a control stick

(Continued)

and buttons in FIGS. 11-13 depict environmental subject matter that form no part of the claimed design.

1 Claim, 10 Drawing Sheets
